M. Elwin
ATTORNEY

UNITED STATES PATENT OFFICE.

FRANK LUSZCZYSZYN, OF LUDINGTON, MICHIGAN.

FREIGHT-CAR BODY.

1,408,214.

Specification of Letters Patent. Patented Feb. 28, 1922.

Application filed August 11, 1921. Serial No. 491,359.

To all whom it may concern:

Be it known that I, FRANK LUSZCZYSZYN, citizen of United States, residing at Ludington, in the county of Mason and State 5 of Michigan, have invented certain new and useful Improvements in Freight-Car Bodies, of which the following is a specification.

An object of this invention is to provide a gondola railway car with effective means 10 for being manually unloaded.

Another object is the means provided by which one or both sides of the car may be raised and disposed in a manner permitting free access by the unloaders.

15 A third object is the provision of means for controlling the car sides and allowing the cargo to be removed direct from the car floor instead of being shoveled over the car sides, a method usually employed.

20 These and other objects are attained by the novel construction and arrangement of parts described in the specifications and shown by the accompanying drawing forming a material part of this disclosure and 25 in which:

Figure 1 is a top plan view of car showing the sides chain supported.

Figure 2 is a side elevational view of the same.

30 Figure 3 is an end view showing by broken lines the sides in open or unloading position.

Referring to the figures in detail the numeral 10 designates in general, car wheels, 35 axles, and trucks of usual design upon which is mounted a car body comprising a floor 11 and ends 12 rigidly attached thereto. Sides 14 and 15 are provided with a plurality of strengthening ribs 16.

40 The sides are positioned between the ends of the car body and may be folded inwardly and downwardly, raised vertically and carried transversely to a point relatively central of the car, these movements being controlled by the projecting ends of the pins or pivot elements 18 secured to the lower end portions of the sides.

45 The projecting ends pass longitudinally through an opening 19 formed by a retaining guide bar 20 angularly formed in spaced conformity with the outline of the car ends. The ends of the guide bars 20 are provided with offset elements 21 adapted to be secured to the lower portion of the car ends 12, the

offsets 21 acting as distance pieces holding 55 the bar 20 away from the car end an amount sufficient to form a slot or opening 19 in which the pivot pins 18 are free to move.

The offset 21 provides a stop on which the pivot pin rests when the car sides are 60 in normal vertical position. A spacing block 22, positioned centrally of the top edge of the car end, is secured by bolts 23 passing through the guide bar 20 and engaging the car ends, the same functioning 65 as a stop for the transverse movement of the sides when in open or elevated position as shown in Figure 3.

By reference to Figure 1 it will be seen that provision against outward displacement 70 of the sides is attained by means of chains 24 and 25 secured to the upper inside portion of the car sides, these chain elements 24 and 25 are adjustably connected one to the other by a lever hook 26 held in closed 75 position by cross link 27.

From the foregoing it will be seen that a simple device for this purpose has been disclosed in the perfect form of its embodiment, but it is not desired to restrict the 80 details to the exact construction shown, it being obvious that changes, not involving the exercise of invention, may be made without departing from the scope of the appended claims.

Having thus described my invention, what I claim as new and desire to secure by Letters Patent, is:—

1. A car body structure comprising a floor, and walls rigidly engaged with said floor, 90 guide bars spacedly engaged over the ends and tops of the said end walls, a pair of side walls disposed between end walls, and pins fixed in said side walls operatively engaging between said end walls and said bars 95 permitting raising said side walls.

2. A car body structure comprising a floor, end elements fixed to extend vertically thereabove, side elements extending longitudinally between said end elements, 100 pins fixed on the lower corners of said side elements, guide bars rigid with said end elements and spaced therefrom, slots in which said pins may operate, and stops central upon the upper edge of said end elements 105 limiting the movement of said side elements.

3. A car body structure comprising a floor having rigid raised end plates, bars

enframing said plates at their tops and ends, said bars framing guide ways, side plates normally resting on said floor between said end plates, blocks interposed in the space 5 between said bars and said end plates at the center along their upper edge, pins fixed on the lower corners of said side plates, said

pins being operable in the mentioned spaces whereby the side plates can be raised and moved over a portion of the top of the car, 10 and means for maintaining said side plates in normal operative position.

In witness whereof I affix my signature.
FRANK LUSCZYSZYN.
